UNITED STATES PATENT OFFICE.

STUART PERRY, OF NEWPORT, NEW YORK.

NAIL-DRIVER.

SPECIFICATION forming part of Letters Patent No. 317,189, dated May 5, 1885.

Application filed October 23, 1884. (No model.)

To all whom it may concern:

Be it known that I, STUART PERRY, of Newport, in the county of Herkimer and State of New York, have invented certain new and useful Improvements in Nail-Drivers; and I do hereby declare that the following is a full, clear, and exact description thereof, reference being had to the accompanying drawings, and to the letters of reference marked thereon, which to form a part of this specification.

The object of this invention is to provide an improved construction in machines for driving-nails—such, for instance, as the one illustrated in Letters Patent of the United States No. 279,427, granted to the present applicant upon the 12th day of June, 1883. In the patent above mentioned a nail-driver is shown which is provided with a driver-head having a passage to receive a reciprocating plunger, by which the nails are driven, and in which the nails are fed to the passage of the said driver-head beneath the plunger by means of a channeled nail holder or magazine, which is removably attached to the head, and provided with a sliding feed-plate having hooks to engage the heads of the nails, and adapted to be actuated by hand to move the nails forward in the channel of the magazine, the said driver-head being provided with devices constructed to successively separate the nails from the line of nails held in the magazine, and to bring and hold said nails in position to be driven by the forward movement of the plunger.

In the device herein shown as illustrating my invention means are provided whereby the nails are fed to the driving devices by gravity, and the said device also embodies improvements in the construction of the devices for separating the nails and for bringing and holding them beneath the plunger, and also in other parts of the apparatus, as will herein-after appear.

In the accompanying drawings, which illustrate a nail-driver embodying the present invention, Figure 1 is a perspective view of the nail-driver with the nail-magazine removed. Fig. 2 is a central longitudinal section of the same. Fig. 3 is a vertical cross-section through the handle or magazine-support with the magazine removed, taken upon the line $\alpha\alpha$ of Fig. 2. Fig. 4 is an enlarged fragmentary side ele-

vation of the driver-head and adjacent parts. Fig. 5 is an end elevation of the nail-driver on an enlarged scale. Fig. 6 is a vertical axial section of the driver-head, taken upon line $\alpha\alpha$ of Fig. 4. Fig. 7 is a side elevation of the plunger removed from the machine. Fig. 8 is a cross-section of said plunger, taken upon line $\alpha\alpha$ of Fig. 7. Fig. 9 is a detail elevation showing the lower surface of the head of the driver. Fig. 10 is a fragmentary perspective view of the rear end of the magazine-holder, showing the devices by which the rear end of the nail-magazine is secured in position. Fig. 11 is a detail bottom view of the pivoted hook or jaw of the driver-head removed from the machine. Fig. 12 is a similar view of the detent. Fig. 13 is a detail sectional view of the hook or jaw, taken upon line $\alpha\alpha$ of Fig. 11. Fig. 14 is a horizontal section of the same, taken on the line $y\ y$ of Fig. 6, showing the position of the parts when the nail is held beneath the plunger, ready for driving. Fig. 15 is a similar view showing the position of the parts after the plunger has been depressed. Fig. 16 is a detail perspective view of the hook or detent shown in Figs. 14 and 15. Fig. 17 is a bottom view of the same. Fig. 18 is a cross-section of the magazine. Fig. 19 is a vertical axial section of the driver-head, showing devices for centering the point of the nail. Fig. 20 is a face view in detail of one of the nail-guides shown in Fig. 19. Fig. 21 is a central longitudinal section of a modified form of the nail-driver, more particularly adapted to drive nails vertically downward. Fig. 22 is a similar view of a form of the driver for use upon ceilings and on horizontal surfaces.

A is a nail-driver, which consists, principally, of a head, A', provided with a central vertical passage, α , constructed to receive and guide a reciprocating driver or plunger, B, and a hollow open-topped handle, A², attached to the said head, said handle, as herein shown, being formed of sheet metal bent in U shape, and having outwardly extended flanges at the top edge of its sides, in the middle portion thereof, to enable it to be conveniently grasped and held by the operator.

C is a removable nail-magazine, which is supported within the hollow handle A², and is adapted to supply nails to the recess α within the head A', in a manner hereinafter described.

The head A' is provided with a vertical slot or aperture, a', through which nails are admitted to the passage a of the head beneath the plunger from the channel of the magazine placed in alignment with said slot, the latter being provided with an enlarged or transverse portion, a', at its upper end for the heads of the nails. Means are provided within the head A' for separating the foremost nail from the line of nails fed to the driving-head from the magazine, for moving the separated nail into the passage a beneath the plunger, and for holding the nail in position for being driven until the descent of the plunger, as will be hereinafter described.

The plunger B is held at the upper limit of its movement by a spiral spring, b, placed around the plunger, between the head b' upon the upper end thereof and the top of the head A', and is, in the operation of the device, forced downwardly to drive the nails by blows from a hammer or mallet. The said plunger, as herein shown, is of cylindric form, and the recess a is of corresponding shape, the head b' being also cylindric, and operating both as a shoulder for the spring and to prevent the body of the plunger from being crushed by repeated blows of the hammer. The spring b is preferably made of flat wire, with its flat side perpendicular to its axis, and is seated in a recess, a', Figs. 2 and 6, formed around the plunger in the upper part of the head A'. The said head A' also is preferably made of approximately the same length or height as the plunger, and is provided in its upper end above the recess a' with a recess, a', adapted to receive the head b' of the plunger when the latter is depressed, whereby the upper end of the head A' operates as a stop to the downward movement of the hammer, so as to relieve the plunger when the latter is struck with unnecessary force, and to thereby enable the latter to be made lighter than would otherwise be practicable. The plunger is provided with a longitudinal slot, b', which is engaged by a stationary stud or projection, b', upon the head A, which operates to hold the said plunger from rotation, and also to limit its upward movement by engaging the lower end of the slot. As herein shown, the stud b' is formed upon a plate, B', which is secured to the exterior of the head by a screw, b', the said stud being constructed to project inwardly through an aperture, b', in the head, as clearly shown in Fig. 2.

The devices for carrying the nails from the slot a' into the passage a and holding them in position for driving are, as herein shown, constructed as follows: Within the head A, opposite the upper end of the passage a', is located an oscillating hook or jaw, D, which is pivoted in a suitable recess in said head, with its axis of rotation parallel with the axis of the passage a, by means of a pivot-pin, D', and a second hook-shaped oscillating or vibrating jaw or detent, D', is pivoted in the said recess concentrically with the jaw D, and with its inner

concave face opposed to the corresponding face of the said jaw, as clearly shown in Figs. 14 and 15. The jaw D is adapted to swing across or over the passage a when rotated, and is provided at its outer or free end with a curved surface, d, concentric with the pivotal point of the jaw, and adapted to close the slot a' when the said jaw is thrown forward across the passage a, as clearly shown in Fig. 14. The outer end of the detent D' is arranged approximately in a radial line with the outer end of the point of the jaw D, and somewhat nearer the pivotal axis of the said jaw than the point of the latter, and the said detent D' is connected with the jaw, so as to move with the latter when it is rotated about its pivotal axis. The jaw is held with its free end over the passage a by means of a spiral spring, d', herein shown, Fig. 2, as placed around the pivot-pin D', which is rotatably mounted in the head A', and is rigidly attached to the jaw D, said spring being connected with the said head and the pin, so as to rotate the latter in the direction to carry the jaw D toward the passage a. Said jaw D also is provided upon its upper surface with a projection, d', having an inner inclined face, d', adapted for engagement with the plunger B, as clearly shown in Figs. 6, 14, 15, and 16, whereby the said jaw D will be thrust aside by the lower end of said plunger in the descent of the latter through the passage a. The outer end or point of the jaw D is so arranged that when the said jaw is thrown laterally by the plunger and held with its inner curved face in alignment with the passage a by the engagement of said plunger therewith, as shown in Fig. 15, the slot will be open to permit the entrance of nails to the passage a. The location of the detent D' is such that a nail passing inwardly from the slot a', when the jaw D is moved backwardly, will come in contact with the outer surface of said detent D' near the point thereof. The radial distance between the outer surface of the detent and the end of the jaw D is approximately equal to the thickness of the shank of a nail, so that when the foremost nail of a line of nails is in contact with the said detent the point of the jaw D will be opposite the space between the said foremost nail and the nail next to it. By this construction it is obvious that the said detent will arrest and hold the foremost nail of the line of nails in such position that in the advance movement of the said jaw D the point thereof will enter between the said foremost nail and the next one of the line, whereby the said foremost nail will be separated from the remainder of the nails in the magazine. The form of the curved inner face of the jaw D is such that in the inward movement of the said jaw, after its point has separated or seized a nail in the manner described, the nail will be carried or pressed inwardly to a point beneath the plunger by the action of the said curved face of the hook and the opposing curved wall of the passage a, toward which it moves. The wall of the passage a

is, as shown, entirely removed to permit the passage of the hook D across it, excepting at a point opposite the central portion of said hook, at which point a connecting part, A³, is 5 provided for uniting the parts of the head A' above and below the recess for the jaw D and detent D², whereby the wall of the passage is made continuous vertically and a support is afforded for the head of the nail, between 10 which support and the said jaw the nail is held in position for driving, as clearly shown in Figs. 6 and 14. By this construction also a smooth vertical face is formed, upon which the nail-head may slide freely downward in 15 the descent of the plunger thereon when the nail is driven. The detent D² is located at the side of the head adjacent to the connecting part A³; and in order to enable the end of the detent to come properly over the passage 20 a when advanced to stop the forward movement of the nails from the magazine said detent is made in hook form, or curved at its central portion, so as to pass around the said part A³ when the point of the detent is advanced, as clearly shown in Figs. 14 and 15.

The spring d' is adapted to hold the jaw normally with its point advanced across the slot a', and with its outer curved surface, d, in 30 position to close the slot a', the detent D² at such time being swung laterally away from the said slot, as clearly shown in Fig. 14. When the device is suitably supplied with nails and is in operation, a nail, N, previously separated and brought inwardly by the jaw D, will be held between the said jaw and the 35 side wall of the passage a whenever the hook is in the position mentioned, as clearly shown in Fig. 14, said nail being obviously held beneath the plunger in position for driving. When the plunger is depressed to drive the nail into the wood, its lower end, upon striking the incline d³, will thrust aside the jaw D, so 40 as to release the nail and to carry the point of said jaw away from the slot a', the detent D² being at the same time moved so as to bring 45 its point across the slot a', whereby the forward movement of the nails through the said slot is arrested. When the plunger returns to its normal position and the jaw D is released, the latter, together with the detent D², 50 will be carried laterally by the spring d', the point of the detent in this movement obviously being withdrawn from contact with the foremost nail of the line of nails at the same moment that the point of the jaw D becomes 55 engaged therewith, so that the said foremost nail is free to be carried inwardly by the curved inner face of the hook D, in the manner before described.

As herein shown, the lower end of the plunger is beveled or inclined to correspond with the inclined face d³ of the jaw D at the point at which it comes in contact with said jaws, as shown at b⁵ in Fig. 6, in order to lessen the 65 wear of the operative surfaces.

In Patent No. 279,427, above referred to as having been granted to me, a nail-driving ap-

paratus is shown provided with a driving-head having a plunger operating substantially as herein described, and with devices for separating and moving the foremost nail in the line into position for driving, consisting of two pivoted jaws operated by the plunger in substantially the same manner that the single jaw herein shown is actuated, and a laterally-reciprocating slide or detent, which is located in front of the inlet-passage of the head, so as to arrest the incoming nails at the time that the jaws are open, and is moved aside by the action thereon of one of the jaws, to allow an inward movement of the nails during the closing of the jaws. The device herein shown and above described operates generally in the same manner as does the device above referred to, the detent D² obviously taking the place of the reciprocating detent or slide shown in the said patent to stop the foremost nail, and to hold it in position to be engaged and carried inwardly by the jaw, and the single jaw D operating in connection with the opposing side 90 of the passage, instead of with an opposing movable jaw, as in the device above referred to. The construction shown, in which the detent is connected with and is operated by a single jaw or hook, possesses obvious advantages in point of simplicity of construction and certainty of action over the one shown in said patent.

In order to prevent the detent D² from becoming injured or broken by striking the surface of a crooked or badly-formed nail, when advanced by the forcible downward movement of the plunger, the said detent is attached to the jaw or hook D by a yielding or spring connection adapted to permit the point of the said detent to yield backwardly a distance equal to or somewhat more than the thickness of a nail. Any well-known or desired device may be used for this purpose; but, as herein shown, the parts mentioned are constructed as follows: The detent D² is mounted to turn freely on the pivot-pin D' of the jaw D, and is connected with said jaw D by means of a projection, d¹, upon the jaw, adapted to engage projections or stops d⁵, formed in or attached to the hub, or part of the detent surrounding the pin, the distance between the stops being slightly greater than the width of the projection, so as to permit a relative movement of the detent with reference to the jaw, for the purpose above stated. The arm and detent are held normally in proper relative position by means of a spiral spring, d⁶, seated in the recess in the cylindrical part or hub of the hook D around the pin D', Figs. 11, 12, and 13. The spring d⁶ is engaged at its inner end with the said hook, and the wire of which it is composed is extended downwardly at its end adjacent to the said detent and engaged with an aperture, d⁷, formed in the latter. The said spring is arranged, in connection with one of the stops d⁵, to hold the points of the detent and hook in proper relative position, the said spring obviously allowing the detent to yield backwardly as far

as permitted by the distance between the stops d^3 , for the purpose above stated.

- The important feature of the construction in the hook or jaw and the detent above described is that whereby the parts mentioned may together be moved by the action of the plunger, so as to carry the nails successively to the passage of the head. For this purpose it is obviously not essential that the said hook and detent should be pivotally supported, as herein shown, since in carrying out this part of my invention the parts mentioned might be arranged to slide in suitable guides, with the general advantages above described. The pivotal construction herein shown is preferred, however, on account of its greater simplicity and ease of operation, and by reason of the comparatively small area of surfaces in frictional contact thereby obtained.
- In the particular construction herein shown the parts are so arranged that the surface of the plunger adjacent to the slot a' is approximately at the same distance from the said slot as the thickness of a nail, the said plunger being, as shown in the drawings, longitudinally grooved or cut away, as indicated at b , Figs. 7, 8, and 15, to prevent contact of the surface of the plunger with the end of the detent D^2 when the latter is in its advanced position. It is obviously practicable, when the parts are arranged in this manner, to dispense entirely with the said detent, and to permit the plunger to act in place of said detent in arresting the inward movement of the nails when the hook or jaw is thrown backwardly, the plunger obviously being in proper position for this purpose at the time mentioned. Inasmuch, however, as the plunger is liable to become worn or grooved by the contact of the nails therewith, the form of the construction herein shown, in which the detent is present, is usually preferred.
- For the purpose of holding and guiding the lower end or shank of the nails in the downward movement of the latter, a laterally-movable guide, E , is arranged upon the head A' below the jaw D , said guide being provided with an inwardly and downwardly inclined surface, e , arranged to extend into the said passage with its lower end in position to hold the nails vertical when the upper ends are held by the said jaw with their heads in contact with the side wall of the passage a , in the manner before described. The said guide is preferably held in its inward position by a suitably-arranged spring, e' , and the inclined surface e of said guide is made concave or hollowed transversely to correspond with the curved form of the inner wall of the said passage, and is constructed in such manner that the said guide will be forced laterally outward by the contact of the lower end of the plunger therewith in the downward movement of the latter, the parts being so arranged that the said inclined surface will come flush with the inner curved surface of the said passage, so as to permit the said plunger and the head

of the nail to pass freely over the said guide in their downward movement. The guide may obviously be held in place by any suitable means adapted to permit the desired lateral movement thereof; but, as herein shown, said guide is pivotally supported upon the head at its upper end by means of a pivot-pin, e^2 , the spring e' being attached to said guide and arranged to press at its free end against the stationary part of the head, so as to throw the lower free end of the guide inwardly.

In the patent upon the nail-driver heretofore granted to me and before mentioned the portable magazines C , for supplying nails to the driving devices of the head A' , were shown as provided with a single nail-channel, and with covers provided with sliding hooks adapted to engage the heads of the nails within the channels, and which were moved by hand to feed the nails forward within the channels to the driving-head.

The feeding devices herein shown are intended to operate by gravity, and for this purpose the nail-magazines C are so constructed as to permit the nails to slide freely through them, and the handle or magazine-support A^2 , in which the said magazine is held, is, when the driver is in operation, held in such position that the nails will gravitate from the channels of the magazine to the said driver-head. This may be accomplished when the handle is located at right angles with the axis of the driving-head, as shown in Figs. 1 and 2 of the accompanying drawings, and also in the patent before mentioned, by holding the driver with the head A' thereof downward in operating upon a vertical or side wall, and in operating upon a horizontal surface—as a floor or ceiling—by moving the hand which holds the driver in such manner as to cause the nails to gravitate into the head after each nail is driven. No particular inconvenience or great decrease in the speed in which the nails are driven will be caused by this means of feeding the nails when operating upon horizontal surfaces; but, if preferred, special forms of the device may be used upon side walls or in driving nails vertically downward into a horizontal surface in which the handle or magazine-support A' is inclined relatively to the axis of the head A' , so as to cause the nails to continually gravitate toward said head when the latter is in operative position. The construction last mentioned is illustrated in Figs. 21 and 22 of the drawings, and will be hereinafter more particularly described.

The magazines C herein shown also differ from the ones illustrated in the patent above mentioned by having, instead of a single nail-channel, two parallel channels, whereby the quantity of nails which may be held at one time in the said magazines is doubled with obvious advantages. In the particular construction of the nail-magazines herein shown said magazines are provided with laterally-movable tops or covers C' , attached to the magazines by spring-connections, whereby said covers

may be moved laterally in filling the magazines. The said magazines are adapted for insertion in a case or tray, by which they may be expeditiously filled—such, for instance, as 5 is shown in the patent above referred to—and the devices for connecting the covers C' with the magazines, as herein shown, are adapted for use in a special form of charging device, which is shown and claimed in another application for Letters Patent filed by me simultaneously herewith.

The covers C' are adapted to permit the nails to slide freely in the channels of the magazines, so that the nails may move freely 15 by gravity in the said channels for the purpose hereinbefore mentioned. The said magazines, as herein shown, Figs. 2 and 18, and as also shown in the application above referred to, are constructed, principally, of 20 sheet metal bent to form two parallel nail-channels, c, separated sufficiently to prevent contact of the nail-heads in the adjacent rows held in the channels, the connecting metal between the channels being bent to form a flat 25 surface or ledge, c', upon which the heads of the nails rest. The metal at the exterior margins of the channels is bent outwardly to form a surface, c'', for the heads of the nails, and is also preferably bent upwardly at right 30 angles with said surface, so as to form upturned flanges c'', to stiffen the upper edge of the magazine.

The tops C' are preferably constructed of sheet metal, and are provided with flanges c', 35 extending downwardly outside of the flanges c'' of the magazine and attached to the upper ends of springs C'', by which the covers are secured to the magazines, and which are adapted to permit the said tops to be moved 40 laterally for the purpose above mentioned, said covers preferably being connected with said springs by means of plates C'', provided with outwardly-projecting curved prongs c'', which operate in a manner and for a purpose 45 fully set forth in the application above referred to.

The channels of the magazines are closed at their outer ends by means of an end plate, C'', provided with a transverse projecting lug, c'', 50 whereby the outer end of the magazine is engaged with the holding devices of the handle A'', as hereinafter described, and the magazine is provided at its inner end with a U-shaped re-enforcing piece, C'', provided with notches 55 c'', adapted for engagement with a suitable holding device upon the head.

For the purpose of supporting the magazine within the handle A'' in such manner that the inner end of the latter may be shifted to bring 60 the channels thereof successively in alignment with the apertures a' of the head, so that when one of said channels has been emptied the other may be brought into position for the passage of the nails therefrom, holding devices are provided as follows: The magazine 65 is held in the handle A'' at its outer end by means of a spring, c'', secured to the end wall

of the handle, and provided with notches c'', adapted for engagement with the projection c' upon the outer end of the magazine, said 70 spring operating by its engagement with the projection to hold the magazine from vertical movement, and at the same time tending to press the magazine longitudinally toward or against the head A''. Upon the side walls of 75 the handle A'', upon either side of the spring c'', are placed two springs, c'', adapted to press inwardly upon the sides of the magazine, and to thereby hold the end thereof from lateral movement. Upon the lateral face of the head 80 A'' adjacent to the slot or aperture a' is placed a transversely-sliding holder or shifting-plate, F, adapted to engage the adjacent end of the magazine and to hold it in position with either of the channels thereof, as desired, in alignment with the said aperture a''. As herein shown, the said plate F is connected with the driver-head, by means of a dovetailed rib, f, upon the plate engaged with a transverse dovetailed slot, f', in the driver-head, 90 and provided with an upwardly-projecting arm, F', adapted to engage a second slot, f'', in the driver-head, so as to assist in maintaining the plate accurately in position. The said plate is provided with a spring- 95 detent, F'', adapted to engage either one of two notches, f'', in the driver-head in suitable position to hold the said plate with either of the channels therein in alignment with the slot a', as clearly shown in Fig. 3, said 100 detent, as herein shown, consisting of a short arm pivoted centrally in a vertical slot in the arm F', and held in position for engagement with the notches f'' by means of a spiral spring, f'', placed between the upper end of 105 the detent and the arm. The plate F is provided with two downwardly-projecting arms, f'', having upon their lower ends two inwardly-projecting lugs, f'', adapted for engagement 110 with the notches c'', formed in the piece C'' at the end of the said magazine, as before mentioned, the covers C' of the magazine, as shown in Fig. 2, terminating a short distance from the end of the magazine which engages the plate F, so that said covers may be opened when 115 the magazine is in the handle for the extraction of a crooked or malformed nail or other purpose. The magazine is inserted in the handle A'' by first engaging its inner end with the shifting-plate F, and then pressing its 120 outer end downwardly upon the spring c'', so as to cause the engagement of the projection c'' thereon with the notch or depression c'' of the spring. The said spring and the shifting- 125 holder F are arranged to support the magazine free from contact with the handle A'', so that the magazine may be moved freely when shifted. The magazine is shifted by first pressing upon the upper end of the spring- 130 detent F'', so as to release it from the notch with which it is engaged, and then moving the plate laterally with the end of the magazine until the detent becomes engaged with the second notch in an obvious manner.

In the particular form of device herein shown the sheet-metal handle or magazine-support A² is attached to the head A' by having its side walls extended over the adjacent sides of the head and provided with inwardly-turned flanges a³, which enter vertical slots a³ in the head, and is secured in place by screws a⁷, which, as shown, are held from jarring loose by washers a⁸, bent upward at one side against hexagonal heads upon the screws, and having inwardly-bent projections engaged with suitable apertures in the metal of the handle to keep them from turning. The slot a' of the head, as clearly shown in Figs. 2 and 9, is extended downwardly through the metal of the handle, so as to form an exit for particles of dirt or detached fragments of iron, which may enter the said slot from the channels of the magazines. A stud or post, a⁹, is shown in the drawings as connecting the parts of the driver-head above and below the recess formed therein for the jaw D and the detent D', so as to give the requisite stiffness in the head, the said stud preferably being screw-threaded for attachment in the head.

The hook A⁴ (shown in Fig. 1 of the drawings) is to enable the driver to be suspended upon a belt worn by the operator or otherwise during intervals of time when it is not being used.

A modified form of the devices for holding the points of the nails in position for driving and for guiding said nails while being driven is illustrated in Figs. 19 and 20, in which two oppositely-arranged guides, E' E', are used instead of the single guide E, hereinbefore described. The said guides are pivoted upon the head A' by means of pivot-pins e⁵, and are held at the inward limit of their movement by springs e⁶ in the same manner as the said guide E. The operative or opposing faces of the guides are transversely concaved, and their lower portions, between which the point of the nail is held, are parallel with each other, and are adapted to hold the nail parallel and in alignment with the axis of the passage a. In the descent of the plunger in driving a nail the latter, after being released from the hook D, is grasped and held vertically in the center of the passage a by the said guides, so that it will be driven perpendicularly into the wood and in exact alignment with the axis of the plunger. The conically-hollowed inner faces of the guide E' are made in their upper part to correspond in cross-sectional contour with the form of the lower end of the plunger, and are set at such an angle with the axis of the driver-head that the latter may engage them at an acute angle, and thereby start them outward with the least possible shock. The guides for the lower end of the nail—either when a single guide is used, as first described, or when two oppositely-acting guides are employed—may be formed in an obvious manner by springs suitably shaped upon their lower ends and attached at their upper ends to the head

A', instead of by spring-actuated pivoted blocks, as herein shown.

G G are spurs having shanks which are received in sockets g in the under side of the head. The spurs or teeth are caused to normally project below the bottom of the head by means of springs g', applied to their shanks and confined within the sockets, each spur having a suitable stop, g², on its shank, to prevent the spring from forcing the latter out of the socket. The spurs are respectively arranged near opposite sides of the head, and are in the shape preferably of curved teeth, which are bent or curved toward one another, so that one or the other of the teeth can be engaged with the edge of a lath nailed, for example, at one point, and the lath thereby drawn into place.

Referring to the modified forms of the nail-driver shown in Figs. 21 and 22, in which the magazines are placed at an angle with the axis of the plunger, the form of the driver shown in Fig. 21 is one adapted for use in driving nails vertically downward. In this case the handle A² is attached to the head A' in such manner that when said head is placed vertically with the exit-opening of the passage a downward the said handle will stand at an upward inclination. The said handle, as shown in said figure, is attached to the head in the same manner as before described, the portion of the body of the head in which the slot a' is formed being extended outwardly, in order to bring the outer face thereof, against which the end of the magazine is placed, at right angles to the handle.

In Fig. 22 a driver is shown for use in overhead work, the handle A² being in this case, when the device is in an operative position, inclined upwardly from its point of attachment to the head A', and the latter being extended upwardly so as to bring its working-face horizontally in line with or above the upper or outer end of the handle. This construction of course necessitates the use of a plunger of considerable length, and one which has a considerable vertical movement. The stroke of the plunger usually, however, need not be more than six inches, so that this feature of operation will not be practically disadvantageous. In other particulars than those above mentioned the devices shown in Figs. 22 and 23 are constructed generally as before described.

In Fig. 21 the driver is shown as provided with guides E, similar to those shown in Figs. 2 and 6. In the form shown in Fig. 22, however, the double guides E' are preferably used, for the reason that a guide device of this form will operate more effectually to accurately guide the nail when making its exit from the extended passage a, after having been carried upwardly in said passage by the plunger, than the single guide hereinbefore referred to.

While the particular magazine or nail-holder above described is particularly adapted for

use in connection with the nail-driver herein shown, the driving devices herein set forth will obviously operate advantageously in connection with any other device adapted to properly feed the nails thereto; and this invention is not, therefore, limited in its scope to a nail-driving mechanism in which the magazine forms a part, except in the claims in which said magazine is specifically referred to.

10 1. I claim as my invention—

15 1. In a machine for driving nails, the combination, with driving devices, of a magazine provided with two or more nail-channels, means for sustaining the said magazine in po-

20 sition for the delivery of nails from the said channels to the driving devices, comprising a shifting support, substantially as described, constructed to hold said magazine with either of its channels in position for delivering nails to the said driving devices, and locking devices 25 for said shifting support, substantially as described.

25 2. In a machine for driving nails, the combination, with a driving-head provided with driving devices and having a side aperture to admit the nails, of a magazine having two or more nail-channels, and means for sustaining the magazine in position for the delivery of nails to the said driving devices, comprising

30 a shifting support, substantially as described, upon the head, constructed to hold said magazine with either of the channels thereof in alignment with the aperture of the head, substantially as and for the purpose set forth.

35 3. In a machine for driving nails, the combination, with a driving-head provided with driving devices, substantially as described, and having a side aperture to admit the nails, of a magazine provided with two or more nail-channels, a fixed support attached to said head and constructed to receive and hold the outer end of said magazine immovable with relation to said head, a shifting support attached to said head constructed for engagement with 40 the inner end of said magazine and adapted to bring either of the channels thereof in line with said side apertures of the said head, and means, substantially as described, for holding said magazine in position with either of channels in line with said aperture, substantially as and for the purpose set forth.

45 4. In a machine for driving nails, the combination, with a plunger, a head having a passage to receive and guide the plunger, and a side aperture to admit the nails into said passage, of a pivoted hook or jaw for separating the foremost nail from a line of nails, means, substantially as described, for actuating the said jaw, the said head being provided 50 with an opposing stationary part or surface operating in connection with the hook or jaw to engage the separated nail and to move the latter bodily forward and into the said passage, substantially as described.

55 5. In a machine for driving nails, the combination of a plunger, a head having a passage to receive and guide the plunger, and an

aperture to admit the nails into said passage, and a single pivoted hook or jaw for separating the foremost nail from a line of nails, 70 means, substantially as described, for actuating the said jaw, said head being provided with an opposing stationary part or surface operating in connection with the jaw to feed forward the separated nail, and also with a 75 part or surface opposed to the jaw and continuous with the inner wall of the passage, and forming, in connection with the said jaw, a means for holding or supporting the nail in position to be driven, substantially as de- 80 scribed.

85 6. In a machine for driving nails, the combination of a plunger, a head having a passage to receive and guide the plunger, and a side aperture to admit the nails to said passage, and a single laterally-movable spring-actuated hook or jaw provided with an inclined surface adapted for engagement with the plunger and operating to separate the foremost nail from a line of nails, the said head 90 being provided with stationary parts or surfaces opposed to the jaw, and forming, in connection with the latter, a means for moving forward into the passage a separated nail and holding said nail in position to be driven, sub- 95 stantially as described.

100 7. In a machine for driving nails, the combination of a plunger, a head having a passage to receive and guide the plunger, and a side aperture to admit nails to the passage, a laterally-reciprocating hook or jaw, means, substantially as described, for actuating said jaw, a vibrating stop or detent for arresting the forward movement of the nails when the jaw is removed from the line of feed, and 105 means, substantially as described, for actuating said detent, the said head being provided with a stationary part or surface opposed to the jaw, and operating, in connection with the latter, to separate and feed forward the foremost nail from a line of nails fed to the driving device, substantially as described.

110 8. In a machine for driving nails, the combination, with a plunger, a head having a passage through it adapted to receive and guide 115 said plunger, and a side aperture to admit nails to the passage, a spring-actuated laterally-reciprocating jaw or hook constructed to separate the foremost nail from the line of nails fed to the driving device and to temporarily close the said aperture so as to stop the nails, and means, substantially as described, for actuating said hook, of a detent adapted to arrest the forward movement of the nails when the said jaw is forced aside by the plunger, and suitable operative connections between the jaw and detent, whereby the latter is actuated from the former, substantially as 120 described.

125 9. In a machine for driving nails, the combination, with a plunger, a head having a passage through it to receive and guide said plunger, and a side aperture to admit nails, a spring-actuated laterally-reciprocating hook 130

or jaw constructed to separate the foremost nail from the line of nails fed to the driver and to temporarily close said aperture, so as to stop the advance of said nails, and provided with an inclined surface adapted to be engaged by said plunger, of a detent actuated by said jaw and adapted to close said side opening when said jaw is forced aside, and a yielding or spring connection between the jaw and the detent, whereby the latter is actuated by the former, substantially as and for the purpose set forth.

10. In a machine for driving nails, the combination, with a plunger, of a head provided with a passage through it to receive and guide said plunger of sufficient length to admit the whole length of said plunger within said head, whereby the outer end of said head acts as a stop to the movement of the hammer, substantially as and for the purpose set forth.

11. In a machine for driving nails, the combination, with the head provided with suitable driving devices, of a spur or spurs mounted in apertures in said head and adapted to project therefrom, said spurs being adapted to engage the piece into which the nails are to be driven, of springs applied to force said spurs outwardly and constructed to yield and permit them to be forced into said head, substantially as and for the purpose set forth.

12. In a machine for driving nails, the combination, with a driver-head provided with suitable driving devices, of a magazine provided with a suitable projection or lug, c^6 , and a magazine-support or handle attached to said head, of means, substantially as described, for supporting the inner end of said magazine, guide-plates c^{10} , adapted to hold the outer end of said magazine laterally immovable in said handle, and a spring, c^8 , adapted to engage said lug c^6 , substantially as and for the purpose set forth.

13. In a machine for driving nails, the combination, with a driver-head provided with means, substantially as described, for driving nails and with a side aperture to receive the nails, a magazine provided with two or more nail-channels, and a magazine-support or

handle provided with supports to receive and hold the outer end of said magazine, of a shifting support for the inner end of the magazine attached to said head and constructed to slide thereon, so as to bring either of said nail-channels in line with said side aperture, and a spring-actuated detent, F^2 , upon the said shifting support, the said head being provided with notches f^3 , adapted for engagement with the said detent, substantially as and for the purpose set forth.

14. In a machine for driving nails, the combination, with a driver-head provided with means, substantially as described, for driving nails, and with a side aperture to admit the nails, a magazine provided with two or more nail-channels, and with notches c^1 at its inner end, of a shifting support for the inner end of said magazine having sliding connection with the head, and provided with projections f^6 , adapted to engage the notches c^1 , and a handle or support for holding the outer end of the magazine provided with a spring, c^8 , adapted to hold the inner end of the said magazine in engagement with the said shifting support, substantially as described.

15. The combination, with a plunger and a driver-head having a passage to receive and guide said driver and a side aperture to admit the nails, of a hook or jaw, D , pivoted to said head and actuated by the plunger, a spring applied to throw the jaw toward the opposing face of the passage, a detent, D^2 , pivotally supported upon the head concentric with the said jaw D , stops d^5 upon the detent adapted to engage a projection upon the jaw for limiting the relative movement of said jaw and detent, and a spring, d^4 , adapted to hold the detent in position for operation, substantially as and for the purpose set forth.

In testimony that I claim the foregoing as my invention I affix my signature in presence of two witnesses.

STUART PERRY.
